Primary Examiner — Darcey E Gottschalk*Assistant Examiner* — Bailey M Knotts(74) Attorney, Agent, or Firm — McGarry Bair PC(57) CLAIM

The ornamental design for a light as shown and described.

DESCRIPTION

FIG. 1 is a top perspective view of a light illustrating our new design.

FIG. 2 is a bottom perspective view thereof.

FIG. 3 is a top view thereof.

FIG. 4 is a bottom view thereof.

FIG. 5 is a front view thereof.

FIG. 6 is a rear view thereof.

FIG. 7 is a right-side view thereof.

FIG. 8 is a left-side view thereof; and,

FIG. 9 is an enlarged view of section 9 of FIG. 1.
